Primary Examiner — Cathron C Brooks*Assistant Examiner* — W. A. Teddy Falloway(74) *Attorney, Agent, or Firm* — AP Patents(57) **CLAIM**

The ornamental design for a receptacle, as shown and described.

DESCRIPTION

FIG. 1 is a front perspective view of a receptacle showing our new design.

FIG. 2 is a front environmental perspective view of the receptacle of FIG. 1.

FIG. 3 is a front view of the receptacle in FIG. 1.

FIG. 4 is a right side view of the receptacle in FIG. 1.

FIG. 5 is a left side view of the receptacle in FIG. 1.

FIG. 6 is a top view of the receptacle in FIG. 1.

FIG. 7 is a bottom view of the receptacle in FIG. 1.

FIG. 8 is a perspective view of another embodiment of the receptacle of FIG. 1.

FIG. 9 is a perspective view of the receptacle of FIG. 1, but shown in a partially open configuration; and,

FIG. 10 is a perspective view of the receptacle of FIG. 1, but shown in a fully open configuration.

The dash-dash broken lines illustrate portions of the receptacle. The dash-dot broken lines represent the bounds of the claim. The broken lines form no part of the claimed design.
